UNITED STATES PATENT OFFICE.

FREDERICK SLOCUM CULVER, OF TAUNTON, MASSACHUSETTS.

LOOP-BANDING MACHINE.

1,161,457.

Specification of Letters Patent.

Patented Nov. 23, 1915.

Application filed August 20, 1914. Serial No. 857,766.

To all whom it may concern:

Be it known that I, FREDERICK S. CULVER, a citizen of the United States, residing at Taunton, in the county of Bristol and State 5 of Massachusetts, have invented a new and useful Improvement in Loop-Banding Machines, of which the following is a specification.

This invention relates to certain new and 10 useful improvements in loop banding machines, and pertains more especially to an improvement on, or attachment for, the machine forming the subject matter of the patent granted June 9, 1903, to F. S. Culver, 15 No. 730516.

The primary object of the invention is to provide means which automatically effects 20 operation of the parts that are necessarily manually operated in the patent above named, which parts will be fully described and set forth in the following specification.

In the drawings, Figure 1 is a side elevation 25 of the machine disclosed in the aforementioned patent, showing the present improvement applied thereto, and Fig. 2 is an enlarged section taken on the line 2—2 of Fig. 1.

The same reference characters are employed in the course of the following description as are used to designate corresponding parts in the drawings of the patent in question.

The standard b^2 and the standard b' support the driving shaft b^3 , the latter having 35 a tight pulley b^4 and loose pulley b^5 . The belt shipper c is pivotally supported and has an arm c' which depends below the bed A' of the machine, which arm is held by the spring c^2 against the stop c^3 when the belt 40 is on the loose pulley. The hand lever c^4 is connected with the rocking support of the belt shipper and is used to move the belt from the loose onto the tight pulley, and in doing this the arm c' of the belt shipper, 45 which engages with the bell crank lever c^5 , is moved to and engages with the second notch of the bell crank lever c^5 , which is held in engagement by the overweight c^6 , and holds the belt on the tight pulley until 50 the belt shipper is knocked off and the spring c^2 draws the arm c' against the stop c^3 , thereby moving the belt from the tight to the loose pulley.

A disk b^{14} is loosely sleeved upon the 55 driving shaft b^3 and provided with a grooved hub d with which hub engages the

forked or bifurcated end of the lever d' . As shown and described in my patent, twister-hooks b^{12} are carried by frames themselves each carried upon a shaft journaled in the standard b^2 , said shaft being intergeared with, and driven from the driving shaft b^3 , and which twister-hooks are actuated by and intergeared with said shaft. The disk b^{14} is provided with a pin b^{13} extending through the standard b^2 and projecting beyond the latter so as to be engaged with and hold the frame against rotation, also as disclosed by my patent.

The lever d' is pivotally supported and is 70 provided with the arm d^2 , the lower end of which engages with the notched bell crank lever d^3 and is held in such engagement by the counterweight d^4 . The spring d^5 tensions arm d^2 . The knock-off rods d^6 and d^7 75 are connected by the rod d^8 with the block a' .

The present invention consists of a vertical lever 1, pivotally connected intermediate its ends at 2 to a bracket 3, which latter depends from the bed A' , the ends of the lever 80 being forked or bifurcated. The lower forked end of the lever 1 straddles the knock-off rod d^6 , while the upper end of the lever has one end of a rod 4 pivotally secured in the fork thereof, the rod being guided in a suitable bearing X^5 to allow sliding movement of same. The lower end of the lever 1 is adapted to abut or engage the coupling X of the knock-off rods d^6 and d^7 , while the 85 rod 4 has its free end for abutting engagement with the arm d^2 .

In the patent in question, the disk b^{14} is necessarily thrown into operation by hand, following which the machine is started by throwing the power into action, which is 90 the cause of considerable trouble due to carelessness on the part of the operator. In the present invention, the action is automatic in that when the rod d^6 moves in the direction of the arrow a , the coupling X will engage 100 with the lower end of the lever 1, thereby sliding or moving the rod 4 so that the latter replaces the arm d^2 into the notch of the bell crank lever d^3 , thus moving the disk b^{14} into proper operative position for starting of the 105 machine. The first twisting having been performed, the end of the rod d^6 will contact with the bell crank lever d^3 thus releasing the arm d^2 and moving the disk b^{14} so as to permit the final operation of the twister 110 head.

Having thus described my invention, I

claim as new and desire to secure by Letters Patent;—

1. In a machine of the type set forth, in combination with a rotatable twister member, rotatable twister-hooks within said twister member, a lever for controlling the operation of the twister hooks, the bell crank lever to engage and hold the controlling lever, and the knock-off rods, a horizontal sliding rod to engage the controlling lever, a vertical lever pivotally connected intermediate its ends to the machine bed and connected at its upper end to the sliding rod, the lower end of the vertical lever being bifurcated and straddling one of the knock-off rods, and means on said knock-off rod to engage the lower end of the vertical lever.

2. In a machine of the type set forth, a rotatable twister frame, twister hooks rotatable independently in said frame, means for holding the frame from rotating, means for throwing said holding means into operative position, a knock-off rod, a sliding rod to operate the throwing means, and connections whereby said sliding rod is operated by the knock-off rod.

3. In a machine of the type set forth, in combination with a rotatable twister frame,

rotatable twister hooks rotatable independently in said frame, means for holding the frame from rotating, means for throwing said holding means into operative position, a knock-off rod, and means whereby upon actuation of the knock-off rod said throwing means will be automatically moved to throw the twister hooks into operative position.

4. In combination with a rotatable twister frame, twister hooks rotatable independently in said frame, means for holding the frame from rotating, means for throwing said holding means into operative position, sliding means to engage and actuate said throwing means, a knock-off rod, and a pivoted means connected to said sliding means and engaged with the rod whereby upon movement of the rod the pivoted means will be actuated to thereby actuate the sliding means so as to automatically move the throwing means into operative position.

In testimony whereof I have signed my name to this specification in the presence of two subscribing witnesses.

FREDERICK SLOCUM CULVER.
